UNITED STATES PATENT OFFICE.

VIRGIL G. JASPER, OF ELYRIA, OHIO.

PENWIPER.

1,347,164.

Specification of Letters Patent.

Patented July 20, 1920.

Application filed May 9, 1917. Serial No. 167,399.

To all whom it may concern:

Be it known that I, VIRGIL G. JASPER, a citizen of the United States, residing at Elyria, in the county of Lorain and State 5 of Ohio, have invented certain new and useful Improvements in Penwipers; and I do hereby declare the following to be a full, clear, and exact description of the invention, such as will enable others skilled in the 10 art to which it appertains to make and use the same.

My invention relates to pen wipers, and more particularly to a device of this type which, while highly efficient, can be cheaply 15 and conveniently made.

Among the objects of my invention are the provision of means for positively wiping and cleaning both sides of the pen at one operation. I also provide means which 20 can be embodied in a structure which it is convenient to carry in the pocket, and which, though used, will not soil the hands or the interior of the receptacle in which it is deposited or carried.

Other objects of my invention and the invention itself will be better understood from a description of the embodiment of the 25 invention.

Figure 1 is a view in perspective of an 30 embodiment of the invention. Fig. 2 is a bottom plan view of the embodiment shown in Fig. 1. Fig. 3 is a sectional view of the embodiment shown in Fig. 1. Fig. 4 is a view similar to Fig. 3, with the parts in 35 operation with pen inserted.

Referring now to the drawing and to the embodiment of the invention illustrated therein, at 5 is shown the main portion or body part of the device, which is preferably 40 made of some resilient material, such as rubber. It will be understood that I contemplate the use of any suitable material. Owing to cheapness in construction, it is more convenient to make the body part 45 of a resilient material integral with and of the same material as the tongue 6.

The tongue 6 is preferably made of rubber and may, as I have said, be integral with the body portion 5, as indicated in the 50 drawing. The tongue may be formed by cutting a slit 7 through the body portion, which approaches a horseshoe or a semi-elliptical shape, the curve at 8 being of substantially the same curvature of writing 55 pen intended to be cleaned with the device. Of course, the curve 8 may be varied to suit

the various types of pens used. I however, prefer to make this curvature a compromise among the curvatures of the various types of pens employed.

The end of the tongue is shown oblique at 9 and a lip *b* is formed upon the lower part thereof. The adjacent wall of the body portion is shown of substantially the same obliquity as the end 9 of the tongue, 60 thus forming a second lip, as shown at *a*. Recesses *c* and *d* are formed on either side of the tongue, preferably by cutting away or gouging out the material of the body portion above and below the tongue. The device may be provided with a handle 11, 65 which may be provided at the one end with a scraper 12.

In operation, the pen is inserted between the end of the tongue 9 and the adjacent wall 70 of the body portion, at substantially the same angle as that of the said wall. In Fig. 3 I have illustrated at *e* in section a portion of a pen which has been inserted in the wiper. Much of the ink and other foreign 75 matter upon the pen will be wiped off in inserting the pen in the slit between the tongue and the adjacent walls of the body portion which are normally in close engagement, so that they must be forced apart 80 when the pen is inserted. The pen may then be straightened a little to the position shown in Fig. 4, and then withdrawn. The lips *a* and *b* will then exert relatively great pressure upon the front and back portions 85 of the pen, wiping it absolutely clean. The foreign matter wiped off will be caught at *f* and *g*, respectively and retained in the recesses *c* and *d*, where it will dry. The dirt 90 being thus deposited in these recesses, the device can be handled or even carried in the 95 pocket without soiling the hands or the pocket. The dirt may be removed from the recesses with the point of a pen knife or other implement.

I have shown this embodiment of my invention and the details thereof for the purpose of better describing the invention. It will be understood that I do not wish to be limited to such embodiment or such details, 100 as numerous and extensive departures may be made therefrom without departing from the spirit of the invention.

I claim:

1. In a pen wiper, the combination of a 110 body part of resilient compressible material and a tongue formed by cutting in the body

part a horseshoe-shaped slit oblique to the top and bottom surfaces of the body part.

2. A pen wiper of resilient compressible material, consisting of a body part and an integral tongue, said body part and tongue being separated by a curved slot to receive the pen, tilted out of the perpendicular with minimum friction, whereby when the pen is moved to decrease said angle of tilt the adjacent portions of the body part and tongue are compressed to grip opposite sides of the pen, the withdrawal of which produces the cleaning of the pen.

3. In a pen wiper, a body portion, a tongue, said body portion and said tongue being composed of resilient, compressible material, said tongue having an outer U-shaped wall, corresponding inner walls for the body portion, said outer and inner walls being normally so close together as to be forced apart when a pen is inserted, and so related as to engage the pen with increased friction when the pen is withdrawn.

4. In a pen wiper, a body portion, a tongue, said body portion and said tongue

being composed of resilient, compressible material, said tongue having an outer U-shaped wall, corresponding inner walls for the body portion, said outer and inner walls being normally so close together as to be forced apart when a pen is inserted, and so related as to engage the pen with increased friction when the pen is withdrawn, said body portion being provided with a dirt-receiving recess on one side of the tongue.

5. In a pen wiper, a body portion, a tongue, said body portion and said tongue being composed of resilient, compressible material, said tongue having an outer U-shaped wall, corresponding inner walls for the body portion, said outer and inner walls being normally so close together as to be forced apart when a pen is inserted, and so related as to engage the pen with increased friction when the pen is withdrawn, said body portion being provided with a dirt-receiving recess above and below the tongue.

In witness whereof I have hereunto signed my name this 5th day of May, 1917.

VIRGIL G. JASPER.
